UNITED STATES PATENT OFFICE.

WILLIAM D. HANSEN, OF CHICAGO, ILLINOIS.

BRUSH.

1,120,476.

Specification of Letters Patent.

Patented Dec. 8, 1914.

Application filed May 25, 1910, Serial No. 563,359. Renewed March 10, 1914. Serial No. 823,795.

To all whom it may concern:

Be it known that I, WILLIAM D. HANSEN, a citizen of the United States, residing at Chicago, in the county of Cook and State of Illinois, have invented new and useful Improvements in Brushes, of which the following is a specification.

This invention relates to brushes and particularly to shaving brushes.

An object of the invention is the provision of a brush or applicator comprising an ordinary brush handle provided with a socket having compactly arranged therein an outer and an inner group of bristles providing a spreading member and a powder retaining member, and owing to the compactness of the inner ends of the groups presents a single mass of bristles disposed axially of said spreading member whereby the maximum flare is given the outer end of said mass.

Other objects of the invention will appear as the specific description which follows is read in connection with the accompanying drawings in which:

Figure 1 is a sectional view of a brush showing the same applied to a face. Fig. 2 is a similar section of the brush. Fig. 3 is a sectional view of a brush showing a modified form of socket.

Referring more especially to the drawings, 1 represents the brush handle to the outer end of which is secured a collar 2 the walls of which produce a bristle socket 3 in which the bristles 4 are properly secured in any suitable manner, as by embedding the same in shellac, rubber, etc.

It will be noticed that the brush body is composed of a solid bunch of bristles, the outer annular row of the same being considerably longer than those of the inner or central bristles. The ends of the central bristles therefore form the base of a socket 5 and the other bristles form the wall thereof.

The outer extremities of the inner group

of bristles are disposed in the same general plane and parallel with the spreading extremities of the outer bristles, thereby forming a cup of such configuration as to permit the brush to be tilted at an angle, say at 45°, when in active use without endangering the loss of the powdered soap and the like material therefrom.

In the modification shown in Fig. 3, the soap receiving socket 6 is formed by gradually decreasing the length of the bristles from the outer portion of the bunch to the inner portion, thereby forming a conical socket with straight walls, the inner bristles forming a base for the socket.

Having thus described the invention, what is claimed is—

A powdered soap applicator comprising, a pliable powder retaining and spreading member including inner and outer groups of bristles, the bristles of the outer group being extended beyond the bristles of the inner group, the said inner and outer bristles being extended toward a common point and being compactly associated at their inner ends to present a single mass of bristles axially of said spreading member, whereby the maximum flare is given the outer end of the latter and the said outer and inner groups of bristles relatively associated at the extreme outer end of the member to define an outwardly flared cup, the said cup having a certain depth longitudinally of the member, and a handle having a common socket into which the inner compact mass of bristles is secured, the outer extremities of the inner group of bristles being disposed in the same general plane and parallel with the spreading extremities of the outer bristles.

In testimony whereof I affix my signature in presence of two witnesses.

WILLIAM D. HANSEN.
